DRIVE FOR DOCTOR OSCILLATORS

George H. Thomson, Worcester, Stephen B. Stafford, Oxford, and Herman A. Smith, Worcester, Mass., assignors to Rice, Barton & Fales, Incorporated, Worcester, Mass., a corporation of Massachusetts

Application April 10, 1931, Serial No. 529,152

3 Claims. (Cl. 101—152)

This invention relates to a drive for operating the oscillator or vibrator rod of a fabric color printing machine which longitudinally vibrates the doctor blade for cleaning the intaglio printing rolls.

The principal object of this invention is to provide a simpler, less expensive, drive than has been used heretofore and which will take up less room. These doctor blade vibrators have been driven in a manner heretofore which takes up a good deal of space and involves the provision of a number of gears and this invention, as stated, is designed chiefly to avoid the complications heretofore thought necessary.

Other objects and advantages of the invention will appear hereinafter.

Reference is to be had to the accompanying drawings, in which

Fig. 1 is a side view of a part of a printing machine showing a preferred embodiment of the invention applied thereto;

Fig. 2 is an end view showing this drive;

Fig. 3 is a side view of a modified form of drive for this purpose in which a motor is used,

Fig. 4 is an end view of the same, and Fig. 5 is a side view showing the connections to the doctor blade.

Referring first to Figs. 1 and 2, it will be seen that the power shaft 10 is provided with a bearing block 11 carried on a bracket 9 which is adjustable through screws 12 on the frame 13 of the printing machine. In order to transmit power from this shaft to the blanket roll shaft 14, a pair of sprocket wheels 15 and chain are employed directly from one shaft to the other. This arrangement, of course, can be made to secure the desired relative rotation between the power shaft and the blanket roll shaft in a very simple manner and employs very few parts.

The cylinder 17 is indicated on which the blanket 18 is carried and which passes over the blanket roll 19 on the shaft 14 and over a pair of idler rolls 20. The blanket roll shaft 14 is mounted adjustably in a fork 21, an adjusting

screw 22 being shown for adjusting it and securing it in adjusted position and the idler rolls are adjusted in a similar manner. The bearing for one of the guide rolls 20 is also adjusted toward and from the other by a screw shaft 25.

This blanket roll 19 is loose on the shaft 14, not being driven by it.

The shaft 14, which rotates constantly, is pro-

vided with an eccentric plate 26 and wrist-pin 27 carried eccentrically and adjustably thereby. The wrist-pin 27 has an eccentric hub 31 rotatably mounted on it. This hub rotates eccentrically in a box 32 which is adjustably connected with the vibrator rod 24. The eccentric rotation of the hub 31 in the box 32 reciprocates the vibrator rod 24 which reciprocates the doctor blade 36 through well-known linkage 37.

In the form shown in Figs. 3 and 4, the mechanism is further simplified by providing a motor 39 which is indirectly coupled to the shaft 14 for operating the rod 24. In some cases enough mechanism is eliminated by this means to warrant the use of the motor. Furthermore by mounting the roll 19 rigidly on the shaft 14, the sprockets 15 and chain can be eliminated. In that case the roll 19 and shaft 14 are driven by the blanket.

Although we have illustrated and described only two forms of the invention we are aware of the fact that other modifications may be made therein by any person skilled in the art without departing from the scope of the invention as expressed in the claims. Therefore we do not wish to be limited in this respect but what we do claim is:

1. In a device for operating the doctor vibrator rod of a textile color printing machine, the combination of a power shaft, a blanket roll shaft, a connection for directly driving the blanket roll shaft from the power shaft, and means connected with the blanket roll shaft for operating a doctor vibrator rod.

2. In a device for operating the doctor vibrator rod of a printing machine, the combination with a blanket roll shaft and a power shaft, of a connection for directly driving the blanket roll shaft from the power shaft, means connected with the blanket roll shaft for operating a doctor vibrator rod, a bearing for supporting the end of the power shaft, a bracket on the frame of the machine carrying the bearing, and adjustable means for supporting said bearing from the bracket.

3. In a fabric color printing machine, the combination with a blanket roll, of a shaft on which said roll is rotatably mounted, a doctor, and means for vibrating the doctor from said shaft.

GEORGE H. THOMSON. 50
STEPHEN B. STAFFORD.
